(57) **CLAIM**

The ornamental design for a door, as shown and described.

DESCRIPTION

FIG. 1 is a front elevational view of my design;

FIG. 2 is a rear elevational view;

FIG. 3 is a top plan view;

FIG. 4 is a bottom plan view;

FIG. 5 is a cross sectional view taken along the line 5-5 of FIG. 1 and viewed in the direction of the arrows;

FIG. 6 is an enlarged fragmentary cross sectional view taken from FIG. 5;

FIG. 7 is a left side elevation view;

FIG. 8 is a right side elevation view; and,

FIG. 9 is a cross sectional view taken along the line 9-9 of FIG. 1 and viewed in the direction of the arrows.

Fig. 3

Fig. 4

Fig. 5

Fig. 6

The diagram shows a circular object. At the top, there is a horizontal line with a small circle at its right end. A curved line descends from this circle, pointing to the center of a dashed circular outline. Inside this dashed circle, there is a horizontal line with a hatched rectangular area below it. The hatched area is bounded by two diagonal lines that meet at the center of the dashed circle. The entire hatched area is filled with diagonal lines.
